UNITED STATES PATENT OFFICE.

JAMES BERNARD KUHN, OF CAMERON, WEST VIRGINIA.

AUTOMATIC STOP FOR MOVING-PICTURE MACHINES.

1,423,948.

Specification of Letters Patent. Patented July 25, 1922.

Application filed August 8, 1921. Serial No. 490,620.

To all whom it may concern:

Be it known that I, JAMES BERNARD KUHN, a citizen of the United States, and resident of Cameron, in the county of Marshall and 5 State of West Virginia, have invented certain new and useful Improvements in Automatic Stops for Moving-Picture Machines, of which the following is a specification.

This invention relates to automatic stops 10 for moving picture machines.

An important object of this invention is to provide an automatic stop for moving picture machines having novel means whereby the machine is stopped when the film 15 fails to feed by the feed sprockets whereby the film is prevented from being entirely broken.

An automatic stop constructed in accordance with this invention will greatly reduce 20 the fire hazards in that the machine is stopped before the film can possibly catch fire.

A further object is to provide an automatic stop for moving picture machines 25 which is positive and reliable in operation and which may be applied to a motion picture machine without elaborately altering the construction of the same.

In the accompanying drawing forming a 30 part of this application in which like numerals are employed to designate like parts throughout the same,

Figure 1 is a perspective of the invention in use.

Figure 2 is a plan view of the improved 35 automatic stop.

Figure 3 is a side elevation of the same.

Figure 4 is an end elevation of the same.

Figure 5 is a fragmentary perspective of 40 a clutch embodied in the invention.

Figure 6 is a perspective of an operating arm embodied in the invention.

In the drawing the numeral 10 generally 45 designates a power transmitting attachment for motion picture machines, the said power

transmitting attachment being adapted for transmitting the power from a suitable motor to a means for feeding the film through the machine in the usual manner. The 50 power transmitting attachment comprises a base 11 having a pair of bearings 12 which rotatably receive a shaft 13 upon which is keyed or otherwise secured a power transmitting pulley 16. The power transmitting 55 pulley is operated from a suitable source of power such as an electric motor by means

of a continuous belt 17 trained about the pulley as illustrated in Figure 1. When the pulley 16 is operated the shaft 13 is rotated thus imparting a rotary motion to a counter 60 shaft 18 rotatably supported by bearings 19 formed integral with the base. A driving connection is established between the counter shaft 18 and the shaft 13 by means of a gear 20 rotatable on the shaft 13 and a 65 larger gear 21 keyed or otherwise secured to the shaft 18.

While the gear 20 is rotatable on the shaft 12 the same is securely connected to the shaft by means of a clutch consisting of a 70 pair of coacting sections 24 and 25, the section 24 being connected to the gear 20 while the section 25 is slidably and non-rotatably mounted on the shaft 13.

The section 25 of the clutch is provided 75 with a sleeve 26 having a pair of oppositely arranged longitudinally extending slots 27 which slidably receive oppositely arranged pins or studs 28 extended from the shaft 13. With reference to Figure 5 it will be noted 80 that the pins 28 have engagement with the side walls of the slots 27 and thereby hold the said section 25 against rotation with relation to the shaft 13.

By reason of this construction the engagement of the section 25 with the section 24 locks the gear 20 to the shaft 13 to cause the shaft 18 to rotate when the shaft 13 is rotated. A driving connection is established between the sections 24 and 25 by 90 means of lugs 28' received within sockets or recesses 30 in the section 24. With reference to Figure 2 it will be observed that the section 25 is urged into driving engagement with the section 24 by means of a coiled 95 spring 31 confined between one of the bearings 12 and the adjacent end of the sleeve 26.

A second gear 33 is keyed or otherwise rigidly secured to the shaft 13 and is adapted to drive a main drive wheel 34 forming a 100 part of the motion picture machine.

With reference to the foregoing it will be observed that the rotation of the pulley 16 will rotate the shaft 13 and consequently the shaft 18. When the shaft 18 is rotated the 105 gear 33 of course will be rotated for operating the gear 34 whereupon the motion picture machine will be operated. As is well known the operation of the gear 34 results in feeding the film through the machine and 110 over a series of feed sprockets one of which is located at the lower portion of the ma-

chine and the other being located at the upper portion of the machine.

As illustrated in Figure 1 the lower sprocket wheel is designated by the numeral 36 and the film 37 is trained over the same and has a loop disposed below the plane of the sprocket. The upper portion of the film 37 passes over the usual feed sprocket and on to the reel in the usual manner.

10 Below the sprocket 36 the film is looped and as the film ceases to feed this loop is taken up by the lower feed sprocket and if the machine continues to operate the film breaks. The film of course ceases to feed 15 when the perforations in the edges of the same do not properly receive the sprocket or when the edge portion of the film is mutilated and no driving connection is provided between the film and the main drive 20 sprocket.

When the film thus ceases to feed, it remains stationary for a sufficient time to catch on fire by reason of the strong ray of light from the machine.

25 It is the purpose of this invention to provide novel means whereby the machine is automatically stopped when the film ceases to feed whereby the strong ray of light to the highly inflammable film is instantly cut off 30 and will remain cut off until the mutilated portion of the film is repaired.

The machine is automatically stopped when the film fails to feed by a longitudinally movable clutch operating arm 39 35 slidably carried by the base and having a laterally projecting fork 40 extended into an annular groove 41 in the section 25.

The longitudinally movable clutch arm 39 is limited in its movement by means of a 40 pin 42 carried by the base and slideable through a longitudinal slot 43 in the arm. With reference to Figure 2 it will be noted that the endwise movement of the longitudinally movable operating arm 39 is limited 45 by the engagement of the pin 42 with the ends of the slot 43. One end of the arm 39 has pivotal connection with a bell crank generally designated by the numeral 45, the said bell crank being connected to the base 11 50 at the juncture of its branches for pivotal movement. The upper portion of the branch 46 of the bell-crank 45 is provided with a pin 47 which is received within holes 48 in opposite sides of the longitudinal slot 49 in the arm 39. Thus it will be seen that the outward or downward movement of the branch 46 will draw the longitudinally movable arm 39 outwardly to disengage the clutch sections 24 and 25 from each other 55 whereupon a driving connection between the pulley 16 and the gear 31 will be broken. As previously stated when the driving connection between the shaft 18 and the shaft 13 is stopped the machine is stopped and the 60 usual fire shutter is dropped.

The bell-crank 45 is provided with a second branch 49' which is engaged with an arm 50 of an operating lever generally designated by the numeral 51. The operating lever 51 is pivoted intermediate its ends to 70 the base 10 as indicated at 52 and is provided at one end with a laterally projecting roller or contact arm 53 which is engaged by the looped portion of the film 37. The roller member 53 is rotatable on a pin 54 carried by the lever 51 and when the tension on the film 37 is increased the roller 53 is elevated for moving the arm 50 downwardly. The tension on the film is increased because of the failure of the film to feed by the feed 80 sprockets when the latter are rotated. When the film ceases to feed the roller 53 is elevated and the arm 50 is lowered for swinging the bell crank on its pivot and thereby moving the operating arm 39 longitudinally. 85

In operation the attachment is attached as illustrated in Figure 1 and when a mutilated portion of the film passes the feed sprockets the film of course will cease to 90 feed and thereby take up the loop with which the roller 53 is engaged. Therefore, the roller or contact member 53 is elevated and the arm 50 is moved downwardly for moving the arm 39 longitudinally and thereby breaking the driving connection between 95 the clutch sections 24 and 25.

When the driving connection between the clutch sections 24 and 25 is broken the machine is quickly stopped though the motor 100 continues to operate and the stoppage of the machine prevents the film from catching on fire.

The driving connection will remain broken until the film is repaired and the attachment again set for operation.

As illustrated in Figure 1 the arm 50 of the lever 51 is offset as indicated at 55 so as to dispose the terminal of the arm 50 at the terminal of the branch 49'. Also the 110 terminal portion of the branch or arm 50 is curved longitudinally and engages the upper edge of the branch 49'. By curving the terminal portion of the branch 50 a shoulder is formed at one side of the branch 115 49 so as to limit the lateral movement of the bell crank in case the pivotal support of the same becomes loose.

Having thus described my invention what I claim is:

1. An automatic stop for motion picture machines comprising a shaft, a clutch section mounted thereon, a longitudinally movable arm having a fork engaging said clutch section, a bell crank engaged with said arm and a film engaging member detachably engaged with said crank and adapted to swing the same on its pivot when the tension on the film exceeds a predetermined point.

2. An automatic stop for motion picture

machines comprising a shaft, a pair of co-
acting clutch sections mounted on said shaft,
a longitudinally movable operating arm having
a forked portion engaging one of said
5 clutch sections, a bell crank engaging said
longitudinally movable arm, a lever having
one end portion engaged with said bell crank,
and a film engaging member carried by said
lever, and adapted to be operated when the
10 tension on the film increases to a predetermined
point whereby to move said arm longitudinally
and disengage said clutch sections.

3. An automatic stop for motion picture

machines comprising a shaft, a pair of co- 15
acting clutch sections mounted on said shaft,
a longitudinally movable operating arm en-
gaging one of said clutch sections, a bell
crank engaging said longitudinally mov-
able arm, a lever having one end portion 20
engaged with said bell crank, and a film en-
gaging member carried by said lever, and
adapted to be operated when the tension on
the film exceeds a predetermined point 25
whereby to move said arm longitudinally and
disengage said clutch sections, and means to
limit the longitudinal movement of said arm.

JAMES BERNARD KUHN.
